INVENTOR
RODOLPHE NAVET.
Mme
ATTORNEY.

UNITED STATES PATENT OFFICE.

RODOLPHE NAVET, OF TUBIZE, BELGIUM.

BRICK PRESS AND THE LIKE.

Application filed February 14, 1924. Serial No. 692,792.

To all whom it may concern:

Be it known that I, RODOLPHE NAVET, a subject of the King of the Belgians, and resident of Tubize, Belgium, have invented 5 certain new and useful Improvements in Brick Presses and the like, of which the following is a specification.

My present invention relates to brick- 10 presses and more particularly to the construction and arrangement of pistons therefor.

In the known presses for the manufacture 15 of bricks, tiles, plates and similar articles, the pressure pistons moved upwardly by the action of a beam, must be moved along a true vertical line, the correct operation of the machine and the perfect shape of the 20 pressed articles being only obtainable if there is no clearance between the cells of the mould or moulds and the mould parts carried by the piston. If the piston is not moved along a true vertical line, said parts of the moulds will be soon worn out.

Now the pressure beam receiving a swing- 25 ing movement in a vertical plane, if as in actual presses, said beam is pivotally connected to or made integral with the pressure piston, the movement of the latter cannot be perfectly vertical.

According to my present invention, the beam and piston are independent from each other, the beam pressing freely under the piston which is provided with one or two vertical guiding rods sliding in sleeves in- 30 tegral with the frame. It is preferred to use the two guiding rod system, particularly for pistons with a plurality of moulds, the steadiness being more surely secured. Broadly stated the invention comprises a guiding 35 arrangement for the piston and an arrangement whereby the piston and beam will be moved upwardly in unison along a true vertical line, the beam being at the same time enabled to move longitudinally with respect 40 to the piston. The latter may be provided at the bottom and centrally with a vertical guide engaged with clearance by the beam so as to prevent the latter from being moved laterally, at the same time enabling the same

to be moved longitudinally within said 50 guide, during its swinging movement and the corresponding upward movement of the piston.

It will be obvious that the novel principle evolved may be applied to hand-presses as 55 well as to engine-presses.

In the system described hereinbefore the transmission of the power of the beam to the piston will be effected directly, whereby the piston and beam will be rapidly worn 60 out at the contact points. This wear will be easily understood if it is considered that the piston moves along a true vertical line whilst the beam moves in a vertical plane around its fixed axis, so that there will be 65 a frictional engagement between the piston and beam. As the power transmitted is a considerable one, the friction will be proportional and the wear a rapid one. Moreover the said friction will produce a con- 70 siderable decrease of the pressure on the piston during its upward movement, that is a decrease of efficiency. As the wear pro- 75 ceeds, the stroke to be run through by the piston for the production of pressed articles of equal thickness will increase, whereby the balance and driving parts thereof will be caused to run through a longer stroke, that is, there will be a further decrease of efficiency or a production of irregular products. 80

The invention also contemplates an ar- 85 rangement having for its object to minimize the wear mentioned and to enable the wear to be easily and rapidly compensated without it being necessary to replace or repair the beam or piston. To this end, I insert between the beam and piston a series of 90 freely revolving rollers and above which is placed a plate forming a carriage, the lon- 95 gitudinal rate of movement of which corresponds substantially to the length of the horizontal projection of the movement of a point of the beam located on the vertical axis of the piston. Thus during the upward movement of the piston, vertical and longitudinal movements will be imparted to said plate, and the latter will be brought automatically back to its position during the

downward movement or unmoulding operation. By this method I furthermore provide for a certain clearance permitting of the piston being guided in a more practical way.

Owing to the use of a plurality of freely revolving rollers adapted to be moved horizontally to a slight extent, the wear of the parts will be considerably reduced and any gripping will be avoided. Moreover the only part subject to wear will be the plate arranged above the rollers (said plate being made of softer metal than the piston) so that the parts may be re-adjusted by replacing said plate.

In the accompanying drawings:

Fig. 1 is a view in elevation, partly in section, of the brick press, showing the parts in their normal positions.

Fig. 2 is a similar view showing the parts in their operative positions.

1 designates the depending end of the piston carrying two vertical guiding rods 2, which are slidably engaged in sockets or sleeves 3 secured to the frame of the machine. 4 is the pressure beam to which movement is imparted in any desired way and which swings around its fixed pivot 5. In the example shown said beam extends below the end of the piston between the vertical rods 2.

The upper face of the beam is provided below the piston with two small angle-irons 6, 6 between which several rollers 7 are arranged on the beam. The space between the angle-irons 6 is filled with rollers, a slight clearance of some millimeters being however provided between the rollers.

Arranged on said rollers is a metal plate 8, made of metal which is less hard than the metal of the rollers, the beam and the piston, so that the wear will be produced only on said plate. Two small angle-irons or two flat bands or strips 9 are secured to the rims 45 of the plate 8, so as to hold the latter continuously on the angle-irons 6 and thus forming a cover fitting nonhermetically, the length of said plate being such that it may be moved longitudinally on the rollers to a distance of 20 to 40 millimeters, that is a length substantially equal the length of the vertical projection of the arc through which is moved any point of the beam located on the vertical axis of the piston.

10 is the discharging lever, pivoted at 11 and actuated in any desired way (of course any other device for lifting the articles out of the moulds may be used). Said lever 10 carries a rod 12 rigidly secured thereto.

Said rod extends for instance through an oblong opening or slot 13 in the beam and forms with the lever 10 an angle so that, when the piston is at the end of its pressure stroke (that is prior to its last upward movement for lifting the articles out of the

moulds), said rod will engage the rim of the plate 8.

As the beam is raised for producing pressure the plate 8 will be moved vertically with it and also longitudinally, thus sliding over the rollers and below the end of the piston. As the articles are lifted out of the mould the piston will carry the lever 10 with it upwardly and the rod 12 will bring the plate 8 back to its initial position, wherein it will remain until the beam will again be raised.

Of course the recoil of said plate may be effected in any other way, say by the action of a spring or springs for instance.

Having now fully described my said invention, what I claim and desire to secure by Letters Patent, is:

1. An improved piston arrangement in presses for the manufacture of bricks, tiles and similar articles comprising in combination the piston, vertical guiding rods rigidly secured to said piston, fixed guides engaged by said guiding rods, a pivotally arranged pressure beam freely engaging the depending end of said piston so that it will be free to be moved longitudinally with respect to said piston, and a wear compensating anti-friction member interposed between the end of the piston and the pressure beam.

2. In a piston arrangement for presses for the manufacture of bricks, tiles and similar articles, the combination of a piston, a fulcrumed pressure beam, a series of rollers inserted between said piston and beam and adapted to freely run between the same, two angle-irons secured on the upper face of the beam to enclose said rollers with a suitable clearance, a plate made of soft metal placed upon said rollers and on which rests the piston, said plate being somewhat longer than the distance between said angle-irons so that it may be moved vertically and at the same time longitudinally, suitable stops at the rims of said plate adapted to engage said angle-irons to limit the longitudinal movements of said plate, and means for effecting the recoil of said plate during or after the operation of lifting the articles out of the moulds, substantially as set forth.

3. In a piston press, a piston movable in rectilinear lines, a pressure beam movable in an arc for operating the piston, and an anti-friction member interposed between the pressure beam and end of the piston, said anti-friction member including a plate more responsive to wear than other portions of the member, whereby to direct the wear of the parts to the plate to permit renewal of said plate as a substantial compensation for wear.

4. In a piston press, a piston movable in rectilinear lines, a pressure beam movable in an arc for operating the piston, an anti-friction member interposed between the piston and beam and comprising a plurality of rollers, means arranged on the beam for

holding the rollers against bodily displacement, a plate arranged upon said rollers and directly engaging the bottom of the piston.

5. In a piston press, a piston movable in rectilinear lines, a pressure beam movable in an arc for operating the piston, an anti-friction member interposed between the piston and beam and comprising a plurality of rollers, means arranged on the beam for

holding the rollers against bodily displacement, a plate arranged upon said rollers and directly engaging the bottom of the piston, the material of said plate being less hard than the metal of the rollers.

In testimony whereof I have hereunto set my hand.

RODOLPHE NAVET.
